UNITED STATES PATENT OFFICE.

THOMAS DROST, OF ELMHURST, AND SOLOMAN SILVERMAN, OF NEW YORK, N. Y., AS-SIGNORS TO THE BRUNSWICK-BALKE-COLLENDER COMPANY, OF WILMINGTON, DELAWARE, A CORPORATION OF DELAWARE.

GULLEY FOR POCKET BILLIARD TABLES.

Application filed May 31, 1923. Serial No. 642,680.

This invention relates to pocket billiard tables and its object is, primarily, to provide a novel system of gulleys for receiving the balls from the pockets and for delivering them to a conveniently disposed receptacle at one end of the table in which they are collected during a game.

The invention also has for its object to eliminate the liability of balls jamming in the gulleys and to facilitate the delivery of the balls to the receptacle by providing a separate and independent gully for each of the pockets through which the balls may roll freely, quietly and easily to the receptacle.

Another important object of the invention is to provide a system of gulleys of inexpensive but substantial material which can be easily made and fitted and as easily re-placed whenever occasion requires.

Another object of the invention is to provide a system of gulleys in which the gulleys for corresponding pockets are interchangeable whereby the assembly or repair of gulleys is greatly facilitated.

Another object of the invention is to provide a system of gulleys constructed of interchangeable parts which simplify and facilitate the installation, and replacement when necessary, of the various tubes; the uniformity in length and construction of the tubes making them available for use and substitution on tables of varying designs and construction of framework.

In the accompanying drawings illustrating a selected embodiment of the invention—

Fig. 1 illustrates a skeleton frame for a table with the gulleys embodied therein in their proper relation.

Fig. 2 is a sectional view on the line 2—2 of Fig. 1;

Fig. 3 is detail enlarged view of a pocket at a corner adjacent the ball receptacle;

Fig. 4 is a similar view of a side pocket;

Fig. 5 is a similar view of a corner pocket at a corner distant from the ball receptacle, and

Fig. 6 is a detail view illustrating the construction of the receptacle which receives the balls from the gulleys.

We have not considered it necessary to illustrate the complete table because tables vary in size and construction and, so far as we are aware, our invention is adaptable to all kinds of pocket billiard tables.

Referring to the drawings, the frame 4 is provided with grooves 5 at the corners at one end and with grooves 6 at the other end for the usual corner pockets and with grooves 7 at the sides for the usual side pockets. The corner grooves are angularly disposed in the usual manner and the side grooves are slightly inclined towards the end of the table which is provided with a receptacle 8 to receive the balls from all of the pockets.

Straight tubes 9—9 are connected to the grooves at the end of the table farthest from the receptacle 8 and these tubes are supported upon and discharge into said receptacle. Straight tubes 10—10 are connected to the side grooves 7—7 and discharge into the receptacle alongside of the tubes 9—9.

Tubes 11—11 curved at 12 between their ends are connected to the corner grooves at the receptacle end of the table and discharge into the receptacle adjacent the tubes 10. The discharge ends of the tubes are arranged in parallel relation, the ends of tubes 9—9 being located side by side at the center, the ends of tubes 10—10 being located beside the tubes 9—9 and the ends of tubes 11—11 being located beside the tubes 10—10, and all of said discharge ends are supported on the rear wall 13 of the receptacle which is

provided with an inclined bottom 14 to direct the balls to the forward part of the receptacle which projects beyond the end of the table or is otherwise conveniently located so that access thereto may be had for removing the balls.

The discharge ends of the tubes are held firmly and rigidly in their positions with respect to the receptacle 8 by means of a lid 23, which is detachably

secured to the receptacle by a plurality of hooks 24.

The tubes are preferably made of paper-board and by this term we include paste-board and fiber-board of sufficient strength for the purpose. We have found in practice that paper-board forms an admirable material for the pocket billiard table gulleys because it can be easily cut to form and size and installed in place. These tubes will exclude dust, they reduce noise of the rolling balls to a minimum and they are light and comparatively inexpensive. We have also found that the inclination of the tubes when installed in a standard table is sufficient to make the balls roll easily and swiftly to the receptacle and since they are separate and independent of each other there is no opportunity for balls to jam in the gulleys.

The gulleys for corresponding pockets are interchangeable, that is to say, the two gulleys 9 are identical in length and end shape and they can be used interchangeably. The same is true of the two gulleys 10 and also of the two gulleys 12. This simplifies the construction and assembly or repair or replacement of the gulleys and reduces the cost thereof.

Each corner groove 5 is preferably provided at its inner end with a block or abutment 15 located at the farthest end of the groove to direct the ball into the gully 9 which is supported at its end on the frame and held in place by the block 16. The groove 5 and the abutment 15 are preferably covered with felt to reduce noise of the ball engaging therewith. A block or abutment 17 is located at the inner end of the groove 7 and this groove and block are also lined with felt to reduce noise. The block is located to direct the ball into the gully 10 which is held in place by the block 18. The groove 6 is turned at an angle at its inner end 19 to direct the ball into gully 11 and this groove is also lined with felt to reduce noise and the gully is held in place by a block 20. We have found that this is a simple and effective means for securing the several gulleys in place and that when the gulleys are cut to the proper length they can be readily assembled in place without fitting or adjustment. To prevent the curved gulleys 11 from becoming displaced by reason of the impact of the ball we prefer to provide a removable cross bar 21 which is held in place by blocks 22 on the frame and against the curved parts 12 of these gulleys 11 whereby the gulleys are held in their proper positions.

The tubes can be withdrawn and replaced at any time without taking off the bed and rails, as it is only necessary to loosen the hooks 24 at the sides of the receptacle 8 and to remove the detachable lid 23. After the lid has been removed, no difficulty will be

met in withdrawing and replacing any or all of the tubes.

Changes in the form, construction and arrangement of the parts may be made without departing from our invention to adapt the invention to tables of different sizes and makes and we reserve the right to make all such changes as fairly fall within the spirit and scope of the invention.

We claim:

1. A pocket billiard table comprising a frame having corner and side pocket grooves, a receptacle at one end of the frame, a pair of straight tubular gulleys connected with the grooves at that end of the table opposite to the receptacle and discharging into the receptacle, a pair of straight tubular gulleys connected to the side grooves and discharging into the receptacle, and a pair of curved tubular gulleys connected to the grooves at the receptacle end of the table and discharging into the receptacle.

2. A pocket billiard table comprising a frame having corner pocket grooves, a receptacle to receive the balls, independent tubular gulleys connected to said grooves and discharging into said receptacle, and abutments in the grooves to direct the balls into the ends of the gulleys.

3. A pocket billiard table comprising a frame having inclined side pocket grooves, a receptacle to receive the balls, separate and independent tubular gulleys connected to said grooves and discharging into said receptacle, and abutments in the grooves to guide the balls into said gulleys.

4. A pocket billiard table comprising a frame having corner pocket grooves at one end thereof, a receptacle at that end of the frame to receive the balls, separate and independent curved tubular gulleys connected to said grooves and discharging into said receptacle, and a cross bar engaged with the frame and with said gulleys to hold the gulleys in place.

5. A pocket billiard table comprising a frame, a receptacle at one end of the frame, a plurality of gulleys for conveying the balls to the receptacle, means secured to the frame for holding the discharge ends of the gulleys in place with respect to the receptacle, and means for detaching said holding means.

6. A pocket billiard table comprising a frame, a receptacle at one end of the frame, a plurality of gulleys for conveying the balls to the receptacle, and a lid detachably secured to the receptacle for holding the discharge ends of the gulleys in operative position relative to the receptacle.

7. A pocket billiard table comprising a frame corner and side pocket grooves formed in the frame, a receptacle at one end of said table, separate and independent gulleys leading from said grooves to said receptacle, and means to support each gully detachably at

the end where it meets a groove, said receptacle supporting the other end of each of said gulleys.

8. A pocket billiard table comprising a frame having corner and side pocket grooves, a receptacle at one end of said table and separate and independent gulleys leading from said grooves to said receptacle, means

to support each gulley at the end where it meets a groove, said receptacle supporting the other end of each of said gulleys, and means for detachably securing said last named end of each of said gulleys to said receptacle. 10
